(57) **CLAIM**

The ornamental design for a bolt-on collapsible stock assembly for a firearm, as shown and described.

DESCRIPTION

FIG. 1 is an upper, right, front isometric perspective view of an exemplary embodiment of the bolt-on collapsible stock assembly for a firearm, wherein the bolt-on collapsible stock assembly for a firearm is in a collapsed position, showing our new design;

FIG. 2 is an upper, right, rear isometric perspective view thereof, wherein the bolt-on collapsible stock assembly for a firearm is in a collapsed position;

FIG. 3 is a lower, right, front isometric perspective view thereof, wherein the bolt-on collapsible stock assembly for a firearm is in a collapsed position;

FIG. 4 is lower, left, front isometric perspective view thereof, wherein the bolt-on collapsible stock assembly for a firearm is in a collapsed position;

FIG. 5 is a right side view thereof, wherein the bolt-on collapsible stock assembly for a firearm is in a collapsed position;

FIG. 6 is a left side view thereof, wherein the bolt-on collapsible stock assembly for a firearm is in a collapsed position;

FIG. 7 is a top view thereof, wherein the bolt-on collapsible stock assembly for a firearm is in a collapsed position;

FIG. 8 is a bottom view thereof, wherein the bolt-on collapsible stock assembly for a firearm is in a collapsed position;

FIG. 9 is a front view thereof, wherein the bolt-on collapsible stock assembly for a firearm is in a collapsed position;

FIG. 10 is a rear view thereof, wherein the bolt-on collapsible stock assembly for a firearm is in a collapsed position;

FIG. 11 is a right side view thereof, wherein the bolt-on collapsible stock assembly for a firearm is in an expanded position; and,

FIG. 12 is a left side view thereof, wherein the bolt-on collapsible stock assembly for a firearm is in an expanded position.
